UNITED STATES PATENT OFFICE.

CHARLES F. KETTERING, OF DAYTON, OHIO, ASSIGNOR TO THE DAYTON ENGINEERING LABORATORIES CO., A CORPORATION OF OHIO.

ELECTRIC MACHINE.

1,191,083.

Specification of Letters Patent. Patented July 11, 1916.

Application filed May 24, 1912. Serial No. 699,400.

To all whom it may concern:

Be it known that I, CHARLES F. KETTERING, a citizen of the United States, residing at Dayton, county of Montgomery, and State of Ohio, have invented certain new and useful Improvements in Electric Machines, of which the following is a full, clear, and exact description.

This invention relates to improvements in timing and distributing devices for ignition systems.

It has been customary heretofore to have a combined timer and distributor for such systems, wherein the timer and distributor are rotated together by a common operating means, the timer intermittently opening and closing the primary circuit of the ignition system, and the distributor serving to distribute the secondary currents to the proper cylinders of the engine, where this ignition system is used in explosive engines, as is well known in the art.

In my previous applications, filed June 3, 1910, Serial No. 564,737, and filed Nov. 14, 1910, Serial No. 592,291, I have shown a combined timer and distributor, wherein the main driving element consists in a central driving shaft. Surrounding this central driving shaft in said other applications, I utilized a sleeve which was termed the distributor shaft and to this sleeve was made fast the timer cam and the rotor of the distributor. Then the central driving shaft was suitably connected to the surrounding sleeve, so that the sleeve would be driven through the medium of the central driving shaft. Then, in order to secure the well known result of advancing the spark in such devices, means were provided as shown in said applications, for producing a relative movement or rotation between the central driving shaft and its surrounding sleeve. The characteristics of said former applications, so far as concerns the comparison with the present system, are the central driving shaft which was connected to suitable engine driven pinions. In this way, the distributor device was adapted to be slipped down upon said central driving shaft and operated accordingly. The device thus mentioned, has been made use of especially in the well known construction of the Cadillac car at the present time, and one of the features of said construction is that the central driving shaft has its own

bearings, thus being provided for in the engine structure.

Now, one of the disadvantages of the former construction referred to, is the necessity of having a central driving shaft provided for and mounted in suitable bearings for proper alinement, to receive the distributor device, when the same is mounted thereon. And moreover, this would naturally result in the necessity of driving said device from one end, so as to preclude the possibility of driving from the side of the distributor device, or from any shaft which is positioned at an angle to the central driving shaft or its surrounding sleeve.

I have found that in certain constructions, it may be desirable to drive from the side, as just explained, and also that it may be desirable to have the driving device self contained in the distributor or timer casting, that is, so as to have the bearings properly self-contained within the distributor and not to be dependent upon any such alinement with the fixed central driving shaft, as above explained.

Therefore, it is a purpose of the present invention to provide such a mechanism for driving the timer and distributor from the side and having bearings self contained, so as to produce what might be called a self-contained-driving-timer and distributor. To bring about this result, I have arranged to drive the distributor directly through the medium of this surrounding sleeve which is properly geared up to any shaft entering the distributor from the side. Then this surrounding sleeve is suitably connected to an internal shaft so as to rotate the latter; and to this internal shaft, is connected the timer cam and the rotor of the distributor. This is, in a way, a reversal of the mode of construction shown in my aforesaid former applications, and it has the new and improved results above mentioned and as will be appreciated more in detail, in following out the construction, use and the advantages which will occur to those familiar with the art.

Another object and one which is ancillary to the above, is to have a combined housing or casing for an electric machine, such as a generator and the timer and distributor, so that said electric generator may have its driving shaft extended directly into the interior of the distributor, so as to drive the

latter from the side, as explained; while the housing referred to, covers both the generator and the operative parts of the distributor, under one inclosing housing or 5 casing. This makes a compact construction and forms a convenient and advantageous support for the distributor, in connection with securing the proper driving of the same.

10 Having thus explained the general objects of the present invention and the more material differences from my former applications, I will now describe in detail the preferred form of embodiment of these improvements, having reference to the accompanying drawings.

In the drawings: Figure 1 is a side elevation of an apparatus embodying the present invention. Fig. 2 is a longitudinal sectional view taken on the line 2—2 of Fig. 3; a portion of the armature and its shaft, together with its driving connection being clearly shown. Fig. 3 is a top plan detail view of the end housing of the generator containing 20 the ignition timing mechanism. Fig. 4 is a detail perspective view of certain of the elements embodying the present invention, shown in disassembled position.

In order to illustrate one instance in 30 which the present invention may be employed with particular adaptability, the ignition timing and distributing mechanism is shown as being combined with an electric generator which is driven by any suitable 35 connection with the prime mover or engine; this generator in turn being employed to drive the timer and distributor mechanism. This preferred form of embodiment of the present invention will clearly illustrate the 40 advantages, in certain cases, of the present invention, over that embodied in my heretofore mentioned co-pending application, filed June 3, 1910, Serial No. 564,737. These differences and advantages will be apparent as the description progresses.

The numeral 20 indicates an electric generator which is provided with the usual complement of pole pieces and field windings (not shown). The armature shaft 21, carrying the armature windings 22, is journaled at one end, in a bearing formed in the end housing 23. This end of the shaft 21 projects outwardly beyond the end housing 23, whereby any suitable driving connection 50 may be made with the internal combustion engine or other prime mover in use. The opposite end housing 24 has an opening within which is mounted the bearing member 25, which in turn supports the opposite 55 end of the armature shaft 21. This end of the shaft 21 is extended into the chamber 26 of the end housing 24 and has a beveled pinion 27 mounted thereon. The chamber 26 contains and supports the ignition timing 60 and distributing mechanism, as well as the

driving element 27, carried by the armature shaft 21. This structure results in what may be termed a self contained ignition timer and distributor. This timing and distributing mechanism comprises a hollow driving shaft or sleeve 28, which is rotatably mounted in the ball or roller bearings 46, secured in the openings formed in the upper and lower walls of the chamber 26. Adjacent to the upper end of the shaft 28, 70 a beveled pinion 29 is mounted and is held in fixed relation thereto, by means of the gib or key 30. This beveled pinion 29 is so positioned that it will engage and mesh with the driving pinion 27, carried by the armature shaft.

It will, of course, be understood that the gear ratio between the pinion carried by the armature shaft and the pinion or gear wheel secured to the shaft 28, will be properly proportioned, so as to operate the timer and distributor mechanism in proper cycle, and at the proper rate of speed, relative to the speed of the engine.

A collar 31 loosely surrounds the sleeve 28, and is formed with an annular groove 32, into which groove, project rollers 33, carried by the yoke arm 34. This yoke may be called the advance yoke, since it is operated to advance or retard the spark, as is customary in mechanisms of this sort. The said collar 31, has extending centrally through it, a pin 35, (see Fig. 4), which passes through a spiral slot 36, formed in the hollow shaft or sleeve 28, and also 90 through the straight slot 37, which is formed in the timer and distributor shaft 38, which in turn fits within the hollow shaft 28.

Referring to Fig. 4, it will be seen that the pin 35 is formed with cylindrical end 105 portions 35^a and a square intermediate portion 36^a. The straight slot 37 formed in the distributor shaft 38, has an enlargement as at 37^a, to permit the passage of the cylindrical ends of the pin 35, therethrough, so 110 as to facilitate the assembling of the shafts 28 and 38, together with the collar 31 and pin 35. The distributor shaft 38 extends upwardly beyond the termination of the driving shaft 28, and adjacent to the upper 115 end thereof, has the timer cam 39 secured thereto. The extreme upper end of this shaft 40 has a driving connection with the rotor 41 of the distributor 42. It will thus be seen that by the operation or swinging of the yoke arm 34^a, the cross pin 35, moving through the spiral slot 36, in the driving member, will cause a further movement of the timer or distributor shaft 38, in which ever direction is desired, either to advance 120 or retard the movement of the timer cam, relative to its normal rotation, inasmuch as the pin 35 passes through the straight slot formed in the shaft 38. By advancing and retarding the movement of the timer cam 125

39, it will be seen that the time of closing and opening the timer contacts 44 and 45, will also be varied with the result that the time of occurrence of the spark in the engine will be varied accordingly. The shaft or sleeve 28, carries suitable roller bearings 46, at its upper and lower ends, each of said bearings being provided with a supporting flange 47, which engages with the walls of the chamber 26, in such a manner that by applying the nut 50 to the screw threaded lower extremity of the shaft 28, the bearing members together with the shaft 28, will be securely held in place.

15 From the above description, it will be seen that it would be practically impossible to combine the timing and distributing mechanism embodied in my co-pending application, heretofore mentioned, with a 20 driving mechanism of the character heretofore described, inasmuch as the shaft or element which carries the timer cam and rotor of the distributor, is, in my co-pending application, the outer sleeve or shaft 28. If 25 this were the case in the present instance, it will be seen that it would be impossible to advance or retard the spark, by any relative movement between the element which carries the timing cam and rotor of the distributor, inasmuch as this outer shaft 28, carries the beveled pinion 29, which meshes with and is driven by the pinion 27, secured to the armature shaft.

By referring to Fig. 3, it will be seen that 35 the driving mechanism for the timing and distributing apparatus, together with the means for effecting the advance and retard of the time of occurrence of the spark, is contained, as heretofore stated, within the chamber 26, formed in the end housing 24. In order to form a container for the timer make and break mechanism, and also to provide a supporting member to receive the distributor cap or head, the end housing 40 directly above the upper wall 51 of the chamber 26, is flanged upwardly as at 52. A detail description of the timer contact mechanism and the distributor mechanism is not deemed necessary in the present case, 45 inasmuch as any suitable devices of this character may be used. However, in the drawings, a specific form has been shown, which is substantially the same as that shown and described in my co-pending applications, filed June 3, 1910, Serial No. 564,737, and filed November 14, 1910, Serial No. 592,291, hereinbefore referred to. Inasmuch as it is desirable to provide a condenser for eliminating any tendency of 50 sparking at the timer contacts 44 and 45, a suitable condenser 53 is secured to the generator and forms a closure or cover for one side of the chamber 26. It will thus be seen that the condenser not only performs the 55 function of eliminating sparking at the

timer contacts, but also forms a closure for the chamber 26.

From the above description of the present invention, it will be seen that the mechanical elements of the ignition timing and distributing mechanism are contained and supported by the end housing of the electric generator, and by constituting the condenser of the ignition system, a cover plate for the chamber, wherein the adjusting and operating parts of the distributing and timing mechanism are contained, it is not necessary to remove the entire end housing of the generator, in order to have access to these parts of the ignition system.

80 Inasmuch as the distributor head 54, which carries the terminal caps 55, for receiving the wires of the secondary circuit of the ignition system, is removable from its support, which in the present instance comprises the flange portion 52, of the end housing; there will be no greater difficulty in removing the end housing, in order to gain access to the interior of the generator, than as if the ignition system were not contained within this housing.

85 While the form of mechanism herein shown and described constitutes a preferred form of embodiment of the invention, it is to be understood that other forms 90 might be adopted, all coming within the scope of the claims which follow.

95 What I claim is as follows:

1. In a distributor mechanism, the combination with a distributor device, and means 100 for rotating the same, including elements constructed to connect the main driving mechanism from the side; an electric machine having a driving shaft connected to said distributor driving means; and a housing covering both said electric machine and said distributor and serving as a support for said distributor, to attach the latter to the side of the electric machine driving the same.

110 2. In a device of the character described, the combination with an electric generator comprising an armature and shaft positioned at right angles to each other; of an ignition timing mechanism; of an end housing for the generator containing and supporting the timing mechanism; and connections between the armature shaft and the timing mechanism for operating the timing mechanism by said shaft.

115 3. In a device of the character described, in combination with an electric generator having an armature and a shaft positioned at right angles relative to each other; an ignition timing mechanism; a cover for said generator, containing said ignition timing mechanism; driving connection between the armature shaft and the timing mechanism; and means contained within the generator cover, operable to advance or retard the 120

125

timing mechanism, independent of the normal actuation thereof, without affecting the operation of the armature shaft.

4. In a device of the character described, 5 the combination with an electric machine having an armature, of an ignition timing and distributing mechanism; an end housing for said electric machine, comprising a casting having a body portion to fit over the 10 end of the electric machine; a bearing positioned in said end housing for supporting said armature, said casting being provided

with a plurality of chambers adapted to contain the timing and distributing mechanism; and means for connecting said mechanism in driven relation relative to the electric machine. 15

In testimony whereof I affix my signature in the presence of two subscribing witnesses.

C. F. KETTERING.
